UNITED STATES PATENT OFFICE.

NOAH SMITH, OF RODERFIELD, WEST VIRGINIA.

EXTENSIBLE FENCE-POST.

1,210,111.

Specification of Letters Patent. Patented Dec. 26, 1916.

Application filed August 5, 1916. Serial No. 113,274.

To all whom it may concern:

Be it known that I, NOAH SMITH, a citizen of the United States, residing at Roderfield, in the county of McDowell, State of West Virginia, have invented a new and useful Extensible Fence-Post; and I do hereby declare the following to be a full, clear, and exact description of the invention, such as will enable others skilled in the art to which it appertains to make and use the same.

The present invention relates to a metal fence post, and has for its object to provide a device of this character which embodies novel features of construction whereby the effective length thereof can be increased or decreased, as desired.

Further objects of the invention are to provide a fence post of this character which can be inexpensively constructed of sheet metal, which can be used in substantially the same manner as an ordinary fence post, which provides means whereby the fence wires can be securely attached to the post, and which can be quickly extended or collapsed.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a telescoping fence post constructed in accordance with the invention, the upper section being shown as telescoped within the lower section. Fig. 2 is a similar view with the upper section elevated. Fig. 3 is a view looking at the post from a position at right angles to that of Fig. 2. Fig. 4 is a vertical sectional view through the post. Fig. 5 is an enlarged horizontal sectional view on the line 5—5 of Fig. 4.

Corresponding and like parts are referred to in the following description and indicated in all the views of the drawings by the same reference characters.

The fence post is formed in two sections which have a telescoping action with each other and can be locked in either an extended condition or a collapsed condition, as de-

sired. The post section 1 has a tubular formation, being preferably formed of heavy sheet metal, and is substantially triangular in cross section. At the upper half of the lower post section 1 the edges of the sheet metal are extended outwardly at one of the longitudinal corners thereof to provide spaced flanges 2, while at the lower half of the post section 1 the edges of the sheet metal are overlapped and secured by suitable fastening members, such as the rivets 3. At the bottom of the post section 1 the edges of the sheet metal may be returned inwardly, as indicated at 1^a, around a reinforcing frame 4, and the said bottom of the post is closed by a plate 5, thereby providing a base which can be embedded in the ground in the usual manner, said base being hollow and formed with water-tight seams so that water will not percolate into the interior thereof. At the top of the section 1 the edges of the sheet metal sides are returned outwardly at 1^b around the sides of a split clamping band 6. The free ends of the clamping band 6 are extended outwardly at 6^a at points adjacent the longitudinal side flanges 2, said outwardly extended ends 6^a being connected by a suitable clamping bolt 7.

The upper post section 8 may also be conveniently formed from heavy sheet metal, and has a cross section corresponding to that of the lower post section 1, being of such a size as to telescope readily within the latter. At the top and bottom of the upper post section 8 the edges of the sheet metal may be returned inwardly, as indicated at 8^a, to engage reinforcing rings or bands 9, and the top of the post section 8 is shown as closed by a plate or cap 10. At the upper portion of the post section 8, the edges of the sheet metal are extended outwardly at one of the corners of the post to provide a longitudinal rib 11, said rib extending from the top of the post section to an intermediate point in the length thereof. From the lower end of the rib 11 to the bottom of the post section 8, the edges of the sheet metal are overlapped and suitably secured as by means of the rivets 12. When the upper post section 8 is telescoped within the lower post section 1, the rib 11 at the upper portion thereof is received within the slotted portion of the lower post section 1, between the side flanges 2 thereof, the portion of the upper section 8 below the rib 11 thereof being received 110

within the basal portion of the lower post section 1.

The split clamping band 6 may be provided at points adjacent the free ends thereof with inwardly projecting studs 13, said studs extending through corresponding openings in the sides of the lower post section 1, and being adapted to engage selected depressions 14 in the sides of the upper post section 8 to positively lock the parts in an adjusted position and prevent them from working loose. When the clamping nut 7 is loosened the upper post section 8 can be moved freely up and down within the lower post section 1, although when the clamping nut 7 is tightened with the studs 13 in engagement with certain of the depressions 14 of the upper post section 8, the latter is securely locked in an adjusted position.

26 The longitudinal rib 11 which extends along the upper portion of the post section 8 is constructed for engagement with the fence wires, being shown as provided with wire receiving slots 15 opening through the edge thereof. Swinging keepers or latch members 16 close the mouths of the slots, locking pins 17 being provided for holding the latch members in a closed position. In a somewhat similar manner the outstanding flanges 2 of the lower post section 1 are formed with wire receiving slots 15^a adapted to be closed by swinging latch members 16^a, said latch members being adapted to be locked in a closed position by pins 17^a.

35 When the upper post section 8 is in a fully extended position, the bottom of the fence wire engaging rib 11 may be above the top of the lower post section 1. In order to bridge this gap between the two members, 40 a fence wire engaging bar 18 is shown as pivotally mounted upon the clamping bolt 7 of the split clamping ring 6, said bar being adapted to be swung upwardly and secured to the rib 11 by a bolt 19, or swung downwardly into an inoperative position against the lower post section 1. This bar 18 may have fence wire receiving slots 15^b therein, keepers or latch members 16^b being provided as in the previous instances for closing the mouths of the slots. The sections of the post may thus be either telescoped within each other or locked in an extended position, and a continuous wire engaging flange member is provided between 50 the top and base of the post when the post is extended.

Having thus described the invention, what I claim as new and desire to secure by Letters Patent, is:—

60 1. A fence post including a tubular lower section having a longitudinal slot in the upper portion thereof, a split clamping band applied to the upper end of the lower section, and an upper section mounted to telescope within the lower section and formed

with a longitudinally extending rib adapted to be received within the slot of the lower section when the two sections are collapsed.

2. A fence post including a tubular lower section having a longitudinal slot in the upper portion thereof and provided with outstanding flanges at the edges of the slot, a split clamping band applied to the upper end of the lower section, an upper section mounted to telescope within the lower section and formed with a longitudinal rib adapted to be received within the slot of the lower section when the two sections are collapsed, the rib of the upper section and the flanges of the lower sections being formed with fence wire receiving notches, and latch members for holding the fence wires in position within the said notches.

3. A fence post including upper and lower sections each formed by rolling a piece of sheet metal and the upper section telescoping within the lower section, the upper section having the meeting edges of the sheet metal extended outwardly at the upper portion to provide a fence wire engaging rib 85 and overlapped at the lower portion below the rib, while the lower section has the edges of the sheet metal spaced at the upper portion thereof to provide a slot to receive the rib of the upper section when the sections are collapsed, the edges at the lower portion of the lower section being overlapped, and means for locking the two post sections in an adjusted position.

4. A fence post including a tubular lower section having a longitudinal slot in the upper portion thereof, a split clamping band applied to the upper end of the lower section and formed with studs projecting into the lower section, and an upper section mounted to telescope within the lower section and formed with a longitudinal rib adapted to be received within the slot thereof when the sections are collapsed, said upper section being also provided with depressions, selected ones of which are adapted to be engaged by the studs of the split clamping band.

5. A fence post including upper and lower telescoping sections, the upper section being provided with a longitudinal wire engaging rib extending downwardly from the top to an intermediate portion thereof, while the lower section is provided at the top thereof with a longitudinal slot adapted to receive the rib of the upper section when the two sections are collapsed, a split clamping band at the upper end of the lower section, and a fence wire engaging bar extending between the clamping band and the rib 115 of the upper section when the said upper section is extended.

6. A fence post including upper and lower telescoping sections, the upper section being provided with a fence wire engaging rib 120

which extends from the top to an intermediate portion thereof, while the lower section is provided at the upper portion thereof with a longitudinal slot adapted to receive the rib of the upper section when the two sections are collapsed, a split clamping band at the upper end of the lower section, a clamping bolt for the clamping band, a fence wire engaging bar pivotally mounted upon the clamping bolt and adapted either to be swung downwardly into inoperative

position against the lower section or swung upwardly and secured to the rib of the upper section when the upper section is extended.

In testimony whereof I have signed my name to this specification in the presence of two subscribing witnesses.

NOAH SMITH.
